UNITED STATES PATENT OFFICE.

HU M. HARRIS AND OLIVER H. ATTRIDGE, OF CHATTANOOGA, TENNESSEE, ASSIGNEES
TO LUCY MANUFACTURING CORPORATION, OF CHATTANOOGA, TENNESSEE, A COR-
PORATION OF TENNESSEE.

ROTARY-DRILLING MACHINE.

Application filed April 20, 1925. Serial No. 24,470.

This invention relates to improvements in oil well drilling apparatus and particularly to what are commonly known in the art as rotaries, this machine being utilized for actually carrying on the drilling operation and for connecting together and disconnecting sections of the well casing.

One object is to provide a rotary having a substantially plane upper face, that is, one in which the upper face of the inner table which supports the work gripping means and the upper face of the outer ring through which rotary motion is imparted to the table are flush with one another.

When the well is being sunk the driven ring and the table supporting the work gripping means are locked together for simultaneous rotation, as is well known, and when it is desired to rotate one section of the casing while the next adjacent section is held fast, as when two sections are being connected together or disconnected, the inner table is locked against rotation while the driven ring is rotated, said ring and table being, at this time, provided with breakout posts for supporting tongs which clamp the casing sections. In known prior constructions, where it is desired to lock the ring and table together, it has been necessary to rotate either the ring or the table with respect to the other until the locking devices have been brought into registry with one another and when it is desired to lock the table against rotation it has also been necessary to rotate said table with respect to its supporting base to bring certain other locking elements into proper relative positions where they may cooperate with one another. The present invention, therefore, seeks to provide means for locking the table and ring together and means for locking the table and base together with but little, if any, adjustment of the table and ring with respect to each other or of the table with respect to the base.

To reduce the friction between the moving parts of the rotary suitable anti-friction elements are provided in the base for supporting the inner table and said table has a well lubricated way in which the driven ring may rotate. It is, of course, essential that these bearings, as well as other portions of the rotary where friction might be

generated, should be properly lubricated and the present invention seeks to provide a novel lubricating system for these parts.

Under ordinary operating conditions the sockets in the ring for the breakout posts often become filled with water, mud or other foreign substances, and a further object of the present invention is to prevent this accumulation of such substances in said breakout posts. As such substances should also be prevented from coming in contact with the anti-friction elements and other lubricating parts, the present invention further seeks to provide means for rendering it impossible for water, mud and the like gaining access to said bearings.

With these and other objects in view the invention consists in certain novel details of construction and combinations and arrangements of parts all as will hereinafter be more fully described and the novel features thereof particularly pointed out in the appended claims.

In the accompanying drawings,

Figure 1 is a plan view of a rotary drilling apparatus constructed in accordance with the present invention.

Fig. 2 is a sectional view on the line 2-2 of Fig. 1.

Fig. 3 is similar view on the line 3-3 of Fig. 1.

Fig. 4 is a sectional view on the line 4-4 of Fig. 1.

In accordance with usual practice the entire rotary is supported upon any desired form of frame work 10 upon which is directly superimposed the base 11 of the rotary. Rotatably supported upon anti-friction elements 12 in the base 11 is the inner table 13 having a central bore for the reception of work gripping means which may consist of a master bushing 14 and the drive bushing 15 through which the well casing or the stem of the swivel extends. For rotating the table there is an outer circular driving ring 16 rotatably supported upon table 13, there being a metal to metal contact between said parts and said ring 16 being adapted to be driven by a shaft 18 provided with a pinion 19 that meshes with a ring gear 20 on the driving ring. The shaft 18 may be supported on the frame work in any suitable way, two longitudinally spaced roller bearing

boxes 21 being shown in the present instance, and power is applied, from any suitable source, to said shaft through a sprocket 22.

- 5 In order that the upper surfaces of the table and ring may lie flush with one another one of said members is formed with an annular projection which is received between vertically spaced shoulders on the 10 other, the top of said annular projection being spaced far enough below the uppermost surface of the rotary so as to permit the upper shoulder on the other member to overlie it and at the same time be flush with 15 the upper face of the member on which said projection is formed. In the preferred construction the ring is formed with an annular interior projection 23 which is received between vertically spaced shoulders 24, 25, 20 on the exterior of the table so that the upper shoulder 25 may overlie the projection on the ring while at the same time the upper surface of said shoulder will be located in the same horizontal plane as the upper surface 25 of said ring. The shoulder 24 has formed therein the way in which said ring runs.

With the projection 23 received between the shoulders on the table, assembly and 30 disassembly of the rotary is greatly facilitated by forming the table in sections, the lower sections of the table being indicated by the numeral 26 and the upper section on which is formed the shoulder 25 being indicated by the numeral 27. In assembling the rotary the lower section 26 is first placed upon the bearings 12, the drive ring 16 is then positioned upon the table 13, and the other section 27 of the table is then positioned 35 in side the drive ring, after which the two sections of the table are rigidly secured together by suitable fastening elements such as bolts and nuts indicated at 28. It will be understood that the bushings are not present in the central bore of the table at this time and ready access may, therefore, be had to the fastening bolts. Likewise, when the rotary is taken down, the bushings are first removed to permit removal of the bolts. 40 The upper section 27 of the table may then be removed.

When the rotary is used for drilling the driving ring is locked to the table so they 45 rotate together on the bearings 12. Heretofore, these parts have usually been locked together by a pawl on the ring adapted to engage in a recess in the table but this arrangement possesses disadvantages in that the recess fills up with dirt and secondly, 50 the ring having previously been moving independently of the table, it often occurs that the recess and pawl are anywhere from a few degrees to one hundred and eighty degrees apart, thus rendering it necessary to rotate 55 either the table or ring relatively to the

other to bring the pawl and recess in registry. In the present case, however, these disadvantages are overcome by providing locking means that cannot clog up with 70 foreign matter and that will be substantially in registry in any position of the ring and table. This novel arrangement comprises one or more projections and a continuous series of indentations on the two members, the indentations preferably taking 75 the form of a continuous series of closely spaced recesses 56 around the periphery of the upper section 27 of the table while the cooperating means consist of a plate 58 slidably secured in a slot 29 in the ring 16 and 80 provided with one or more, usually about four, projections or teeth 30. By making the width of the teeth a little less than the space between adjacent recesses it is apparent that the teeth or projections and the 85 recesses will always be so positioned as to enable the projections to enter a corresponding number of recesses with but little, if any, adjustment of the table and ring. Furthermore, by having the recesses formed in 90 the periphery of the table they can be formed with open bottoms so that no foreign matter can accumulate in them. Suitable means are provided for sliding plate 58 back 95 and forth, the mechanism contemplated comprising a cam 31 journaled on a vertical axis on the ring and working in a slot 32 in the plate. The cam is held down on the ring by a spring 33 interposed between it and an overhanging portion of said ring and by 100 rocking a hand lever 34 on the cam, the plate may be slid back and forth to move the projections into or out of engagement 105 with the recesses in the table.

As has been stated the rotary is also used 110 for breaking or making joints in the string of casing and under these circumstances the projections 30 must be disengaged and table locked against rotation while the ring alone 115 is rotated. To lock the table against rotation for this work there is a vertically disposed pin 35 slidably held in the base 11 by a cam 36 on a horizontally disposed shaft 37 journaled in said base. When the table is 120 rotating with the ring the upper end of the pin lies below the top face of the base but when the table is to be locked against rotation, shaft 37 is rocked by a hand lever 38 thereby causing cam 36 to elevate the pin 125 above the base against the tension of spring 39. When elevated, the upper end of pin 35 is received in one of a continuous, circular series of sockets 40 in the bottom face of the table and by locating adjacent sockets close together, there will be little or no necessity of rotating the table on the base to bring a socket into registry with the pin. The usual breakout posts for the tongs are supported in the sockets 41 and 42 in the 130 table and ring when the joints are being

made or broken as will be understood, and the posts and tongs are not, therefore, illustrated.

It is also a common occurrence for the breakout post sockets to fill up with foreign material, such as mud being washed in the sockets. For this reason each socket in the present apparatus has a drainage passage near its bottom to prevent the collection of mud and water therein. The drain passage for the socket 42 in the ring is shown at 43 leading from said socket to the periphery of the ring and the passage for socket 41 in the table is shown at 44. Passage 44 leads to the central bore as mud between the table and bushings will do no harm whereas, should the mud get between the table and ring it would have access to the lubricating system hereinafter described. In this connection, attention is called to the fact that mud or the like entering the space between the ring and table, at the top of the latter, cannot gain access to said lubricating system in the present rotary. This is prevented by interposing packing 45 between the table shoulder 25 and ring flange 23, the packing preferably being secured in an annular recess in a bead 46 formed on the upper face of said flange. Also the accumulation of mud or water in this space is prevented by one or more drains or ducts 47 leading to the breakout post socket 42 from a groove 48 formed in the upper face of ring flange 23 at a point intermediate the bead 46 and the outer edge of shoulder 25.

In the preferred arrangement for lubricating the rotary, a reservoir 49 is provided in the ring 16 and communicates through suitable ducts with the contacting portions of the ring and table. A bath of oil is thus provided for the way in which the ring rotates, the oil collecting in said way until it overflows the outer side wall of the way, from whence it flows downwardly between the lower table section and a depending skirt 50 on the ring, lubricating the bearing surfaces of these portions. Passage of oil from the inner to the outer side of the way is permitted by the provision of radial ducts 57 in the bottom face of ring 23. By providing a series of ducts 51 in the skirt 50, a portion of the oil will be diverted to lubricate the bearing surfaces of said skirt and the hold down ring 52 which is generally used for holding the table and ring on the base 11. Wear on the cooperating surfaces of the drive ring and the hold down ring may be compensated for by the use of shims 53.

The oil flowing down between the skirt 50 and the lower table section is caught in a trough or reservoir 54 in base 11 until it reaches the top of the side wall of the trough next to the bearings 12, this wall of the trough being lower than the opposite wall. After the oil has accumulated in the trough

to this extent it will flow into and collect in the raceway of bearings 12, providing a bath for the latter. From this raceway, the oil will flow toward the central bore of the table, the inner side wall of said raceway being lower than the other, so that it will then lubricate the bearing surfaces of a skirt 55 on the table and the adjacent encircling portion of the base 11. In this way the anti-friction elements 12 as well as substantially all of the friction surfaces in the rotary are lubricated from a single source of supply and it will be noted that there is little likelihood of foreign substances coming in contact with the lubricant after it leaves the reservoir 49 by the packing 45.

What we claim is:

1. In a rotary drilling machine, the combination of a base, a concentrically arranged inner table having upper and lower sections and outer ring supported by said base, said inner table having a central bore, and work gripping means in said central bore, an integrally formed portion of the lower section of said inner table projecting radially outward to form a ledge on which the ring is supported and a portion of the upper section of said inner table projecting radially outward to overlie said ring with the top surfaces of said table and ring lying in the same plane.

2. In a rotary drilling machine, the combination of a base, an inner table formed of upper and lower sections, rotatably supported on the base, an outer ring, an integral annular ledge on the lower section of the inner table underlying said ring, a bearing surface on said ledge on which the ring is rotatably supported, and a projection on the upper section of said inner table overlying said ring with the top surfaces of said table and ring lying in the same plane.

3. In a rotary drilling machine, the combination of a base, a concentrically arranged inner table having upper and lower sections and outer ring supported by said base, said inner table having a central bore, work gripping means in said central bore, an integral portion of the lower section of said inner table projecting radially outward to form a ledge on which the ring is supported and a portion of the upper section of said inner table projecting radially outward to overlie said ring, hold down means for limiting axial movement of the table and ring with respect to the base, and means for releasably locking the table and ring together for simultaneous rotation.

4. In a rotary drilling machine, the combination of a base, an inner rotary table bearing on the base, an outer rotary ring, said inner table being formed in sections with an integral portion of one section providing a bearing for the ring and a portion of the other section overlying said ring, and

work gripping means carried by said table, the upper surfaces of said ring and the overlying portion of the table lying in the same plane.

- 5. In a rotary drilling machine, the combination of a base, a rotary inner table having a central bore and an annular recess in its exterior surface forming upper and lower shoulders, and an outer rotatable ring supported on the lower shoulder of the table with said upper shoulder overlying a portion thereof, the top surface of the upper shoulder and said ring lying in the same plane.
- 6. In a rotary drilling machine, the combination of a base, a rotary inner table, work gripping means carried by said table, an outer rotatable ring, and means for locking said table and ring together for simultaneous rotation, said means comprising a continuous series of indentations around the table, a comparatively short series of projections movably supported on the ring, and means for moving said short series of projections into and out of engagement with a corresponding number of indentations in the table.

7. In a rotary drilling machine, the combination of a base, a rotary inner table, work gripping means carried by said table, an outer rotatable ring, and means for locking said table and ring together for simultaneous rotation, said means comprising a continuous series of closely positioned indentations extending around the table, a plate slidably mounted on the ring, a comparatively small number of projections on said plate, and means for sliding said plate toward and from the table to move said teeth into and out of engagement with the indentations in said table.

8. In a rotary drilling machine, the combination of a base, a rotary inner table, work gripping means carried by said table, an outer rotatable ring, and means for locking said table and ring together for simultaneous rotation, said means comprising a continuous series of closely positioned indentations extending entirely around the table, a slideable plate on the ring, a plurality of projections on said plate, a cam cooperating with said plate and means for rotating said cam to slide the latter toward or away from the table and thereby effect the engagement or disengagement of said projections and indentations.

9. In a rotary drilling machine, the combination of a base, an inner rotary table on the base, work gripping means carried by the table, an outer rotatable ring, said table being formed in two sections each of said sections having a series of recesses therein, removable means for rigidly connecting said sections, a plurality of projections on the ring cooperating with said series of recesses

for locking the table and ring together and means on the base adapted to cooperate with the other series of recesses for holding the table against rotation.

10. In a rotary drilling machine, the combination of a base, an inner rotary table, an outer ring having breakout post sockets extending below its upper surface with a clean out passage leading from each socket to a side face of said ring, means for driving said ring and table, and means for locking the table against rotation.

11. In a rotary drilling machine, the combination of a base, an inner rotary table adapted to support work gripping means, an outer rotary ring, said table and ring partially overlapping one another at their upper surfaces, said ring having a breakout post socket therein with a drainage passage leading from said socket to an exterior face of the ring to prevent accumulation of foreign matter in said socket and a drainage passage leading to said socket from the space between the overlapping portions of the table and ring, and means for locking the table against rotation.

12. In a rotary well drilling machine, the combination of a base, a rotary inner table having a central bore and adapted to carry work gripping means, a rotary outer ring having an inwardly extending portion forming a ledge underlying a portion of the inner table, said ring having sockets therein for breakout posts with drainage passages extending from the outer edge of said ledge to said sockets and from said sockets to the exterior face of said ring, and means for locking the inner table against rotation.

13. In a rotary well drilling machine, the combination of a base, a rotary inner table having a central bore and adapted to carry work gripping means, a rotary outer ring having an inwardly extending portion forming a ledge underlying a portion of the inner table, said ring having sockets therein for breakout posts with drainage passages extending from the outer edge of said ledge to said sockets and from said sockets to the exterior face of said ring, means between the inner edge of the ledge and the first mentioned passages for preventing passage of water and other foreign substances to the inner edge of said ledge.

14. In a rotary well drilling machine, the combination of a base, a rotary inner table having a central bore and adapted to carry work gripping means, a rotary outer ring having an inwardly extending portion forming a ledge underlying a portion of the inner table, said ring having sockets therein for breakout posts with drainage passages extending from the outer edge of said ledge to said sockets and from said sockets to the exterior face of said ring, and packing in the upper face of the ledge for prevent-

ing water and other foreign substances passing inwardly to the inner edge of said ledge.

15. In a rotary well drilling machine, the combination of a base, an inner table adapted to support work gripping means, a driving ring rotatable on said table, means for locking said ring and table together for simultaneous rotation on said base, a bearing surface on said table for said ring, and anti-friction elements between said table and base, there being a lubricant reservoir in said ring for supplying lubricant to the bearing surface of the table, and a trough in said base beneath the ring and outer surface of the table to receive lubricant overflowing from said bearing surface, said trough being located adjacent the bearings between the table and base and draining in a direction toward said bearings to lubricate the latter.

16. In a rotary well drilling machine, the combination of a base, an inner table adapted to support work gripping means, a driving ring rotatable on said table, means for locking said ring and table together for simultaneous rotation on said base, a bearing surface on said table for said ring, anti-friction elements between said table and base and a hold down ring overhanging a portion of the driving ring, there being a lubricant reservoir for supplying lubricant to the bearing surface of said table, to said anti-friction elements and to the abutting surfaces of the two rings.

35 17. In a rotary drilling machine, the combination of a base having a central bore, a table rotatable on said base, said base having a lubricant receiving recess and a raceway therein, anti-friction elements in said

raceway for supporting said table, a drive ring rotatable on said table, a bearing surface on said table for said ring, and a lubricant reservoir in said ring communicating with the bearing surface of said table, there being a space between said table and ring through which lubricant will flow from the bearing surface of the table into the recess in the base, the side wall of said recess nearest the anti-friction elements on the base being lower than the opposite side wall whereby excess lubricant flowing into the recess will overflow toward said anti-friction elements.

18. In a rotary drilling machine, the combination of a base having a central bore, a table rotatable on said base, said base having a lubricant receiving recess and a raceway therein, anti-friction elements in said raceway for supporting said table, a drive ring rotatable on said table, a bearing surface on said table for said ring, and a lubricant reservoir in said ring communicating with the bearing surface on the table, there being a space between said table and ring through which lubricant will flow from said bearing surface of the table into the recess in the base, the side wall of said recess nearest the anti-friction elements on the base being lower than the opposite side wall whereby excess lubricant flowing into the recess will overflow toward said anti-friction elements, and the side of the raceway in the base nearest the central bore being lower than the other side wall of said raceway whereby lubricant will flow from said raceway to the surface of said central bore.
